UNITED STATES PATENT OFFICE.

LOUIS H. PETRUS, OF KANSAS CITY, MISSOURI.

SANDING DEVICE FOR MOTOR VEHICLES.

Application filed January 13, 1926. Serial No. 80,985.

To all whom it may concern:

Be it known that I, LOUIS H. PETRUS, a citizen of the United States, residing at Kansas City, in the county of Jackson and 5 State of Missouri, have invented certain new and useful Improvements in Sanding Devices for Motor Vehicles, of which the following is a specification.

My invention relates to sanding devices 10 for motor vehicles and the present invention is an improvement over the sanding device disclosed by my United States Letters Patent No. 1,555,153, granted September 29, 1925.

One improvement resides in mounting 15 the lower ends of the sand boxes upon hinges, so that their upper ends can be lowered upon the rear tires of the vehicle to permit ready access to the openings through 20 which said sand boxes may be filled with sand or other gritty substances.

A further improvement resides in the fastening means for firmly securing the upper ends of the sand boxes against the under 25 surfaces of the vehicle fenders, said fastening means being arranged entirely beneath the fenders where they will be out of sight and not mar the appearance of the fenders.

Another improvement resides in mechanism 30 whereby the valves which normally close the discharge nozzles at the lower ends of the sand boxes can be either opened together or independently of each other.

Other improvements in certain details of 35 construction have also been made, and in order that the invention may be fully understood, reference will now be made to the accompanying drawing, in which:

Fig. 1 is a broken perspective view of a 40 motor vehicle equipped with the invention.

Fig. 2 is a vertical section through one of the sand boxes and the fender against which it fits.

Fig. 3 is a broken cross section of one of 45 the rear fenders and associate apron, with the upper rear portion of one of the sand boxes secured in position against the underside of said fender.

Fig. 4 is a fragmentary side elevation, 50 partly in section, of the lower portion of one of the sand boxes and associate parts.

Fig. 5 is a broken elevation of the instrument board with the mechanism for opening the valves at the discharge nozzles of 55 the sand boxes.

Fig. 6 is a section on line 6—6 of Fig. 5.

Fig. 7 is a broken side elevation of a truck equipped with a modified form of sand box.

Referring now more particularly to the parts disclosed by Figs. 1 to 6, inclusive, 60 2 designates a motor vehicle of conventional form equipped with the usual rear fenders 4, rear wheels 8 and an instrument board 10.

12 designates the sand boxes, or receptacles, which are curved to fit snugly against the undersides of the fenders 4 and in front of the rear wheels 8 for the purpose of depositing sand or other gritty substances in the path of said wheels. Each sand box 70 has an opening in its upper portion through which it may be filled with sand or other gritty substance, and said opening is normally closed by a cover 14.

The lower end of each sand box 12 is provided with a discharge nozzle 16 which is normally closed by a valve 18 similar to those shown in my above-mentioned patent and consisting of a flat plate which fits snugly against the lower edge of said nozzle 16.

The valve 18 is protected from mud by a shield 19 at the lower end of the sand box 12 and extending around the front, rear and one end of said valve 18. Each valve 18 is loosely mounted upon guide pins 20 depending from the lower portion of the associate sand box 12. One or more coil springs 22 are employed for yieldably holding each valve 18 in closed position. Each coil spring 22 is connected at its lower end to a short 80

length of cable 24 which extends through the valve 18 and is secured by a clamp 26, while the upper end of each spring 22 is connected to the lower end of a short cable 28, which is connected at its upper end to a 90

tensioning device preferably in the form of a turn buckle 30, the upper eye of which is mounted upon a pin or bolt 32 extending transversely through the upper portion of the sand box 12. As shown more clearly by 100

Fig. 2, the turn buckle 30 is arranged beneath the cover 14, so that when the same is removed access may be had to said turn-buckle 30 to adjust the same for the purpose of regulating the tension of the spring 22. 105

Each sand box 12 is held in position against the underside of the associate fender 4 by means of a plate 34 and a fastening device 36. The plate 34 is connected to a suitable portion of the motor vehicle 2, such for instance, as the running board 38, while the fastening device 36 is preferably connected 110

at its lower end to the associate vehicle apron 40 in such position that when swung upwardly to engage the underside of the sand box, as shown by Fig. 2, it will force 5 the same firmly against the underside of the fender A. The fastening device 36 is prevented from swinging rearwardly out of engagement with the sand box 12 by a suitable latch 42 connected to the upper end of the 10 sand box by a pivot 44. The plate 34 is connected to the lower end of the associate sand box 12 by means of a hinge 46, so that when the fastening device 36 is disengaged from the upper end of said sand box 12 the same 15 may swing downwardly and rest upon the tire 48, so that access may be readily had to the cover 14 when the sand box 12 is to be filled, or the turn buckle 30 adjusted.

Referring now to the mechanism whereby 20 the valves 18 may be opened either together or independently of each other for the discharge of sand in advance of both or either rear wheel 8, 50 designates a pair of curved arms secured at their upper portions to the 25 valves 18, and connected at their lower ends to the rear ends of flexible cables 52 extending forwardly through tubes 54 and secured to the shanks 56 of knobs 58 arranged within convenient reach of the driver. As shown 30 more clearly by Fig. 6, the shanks 56 extend through openings 60 and 62 in the instrument board 10 and a plate 64, respectively. The knobs 58, which normally rest against the face of the plate 54, are spaced apart to 35 admit a larger knob 66 mounted upon a shank 68 which is fixedly secured to the plate 64 and extends through an opening 70 in the instrument board 10. A coil spring 72 extending around the shank 68 and interposed between the instrument board 10 and a washer 74, yieldably holds the plate 64 against the instrument board 10. The washer 74 is held from displacement upon 40 the shank 58 by a nut 76 and operates in a tubular guide 78 secured to the underside of the instrument board 10.

When it is desired to discharge sand from 50 only one of the sand boxes 12, the proper knob 58 is pulled outwardly towards the driver, and when it is desired to simultaneously discharge sand from both sand boxes 12 the knob 66 is pulled outwardly to cause the plate 64 to pull both of the knobs 58 outwardly. The cables 52 are normally held 55 slack to permit the valves 18 to remain closed, by coil springs 80 secured to eye bolts 82 and clamps 84, which latter are secured to the cables 52. The clamps 84 also prevent the valves 18 and the springs 22 from 60 being subjected to undue strain when said valves 18 are opened by abutting the rear ends of the tubes 54 and thereby checking the forward movement of the cables 52.

In the modified form, Fig. 7, I have shown 65 the sand box 12^a attached to the underside of

the body 2^a of a heavy duty truck. The sand box 12^a is filled through an opening in its upper portion which is normally closed by a cover 14^a, while the lower portion of said sand box has a discharge nozzle 16^a similar 70 in construction to the nozzle 16 and from which the discharge of sand may be controlled by the same type of mechanism. The nozzle 16^a is arranged to discharge upon the wheel 8^a instead of in advance of said wheel, 75 so that the sand will be carried around under the wheel whether the same be traveling forward or backward. It is to be understood that a sand box will be arranged over each wheel 8^a. 80

While I have referred to the receptacles 12 and 12^a, as sand boxes it is to be understood that they may be supplied with any gritty substance that will prevent the vehicle wheels from skidding. I also reserve the 85 right to such changes and modifications in the construction shown and described as properly fall within the spirit and scope of the invention as claimed.

Having thus described my invention, what 90 I claim and desire to secure by Letters Patent, is:

1. In a sanding device for motor vehicles, a receptacle adapted to fit against the inner surface of the vehicle fender and provided 95 with an inlet and an outlet, means operably connecting the lower portion of said receptacle to the vehicle so that its upper portion may be lowered to expose the inlet, and securing means for holding the upper portion 100 of the receptacle in raised position.

2. In a sanding device for motor vehicles, a receptacle adapted to fit against the vehicle fender and provided with an inlet and an outlet, hinged means operably connecting 105 the lower portion of said receptacle to the vehicle so that its upper portion may be lowered to expose the inlet, and securing means for holding the upper portion of the receptacle in raised position. 110

3. In sanding devices for motor vehicles, receptacles adapted to fit against the inner surface of the vehicle fenders and provided with inlets and outlets, means operably connecting the lower portions of said receptacles to the vehicle so that their upper portions 115 may be lowered to expose the inlets, and fastening devices pivotally connected to the vehicle for holding the upper portions of the receptacles in raised position. 120

4. In a sanding device for motor vehicles, a receptacle having a discharge nozzle, a valve, spring means arranged within the receptacle for yieldably holding said valve in closed position against the lower edge of 125 said nozzle, and a turnbuckle for regulating the tension of said spring means.

5. In a sanding device for motor vehicles, a receptacle having a discharge nozzle, a valve, spring means arranged within the re- 130

ceptacle for yieldably holding said valve in closed position against the lower edge of said nozzle, and a shield on the receptacle extending around the nozzle and below said

5 valve.

6. In sanding devices for motor vehicles, receptacles adapted to fit against the rear wheel fenders of the vehicle and provided with discharge openings, valves, spring 10 means for yieldably holding said valves in position to close said openings, connections whereby either valve may be opened independently of its companion, and means for simultaneously actuating said connections to 15 cause the valves to open together.

7. In sanding devices for motor vehicles, receptacles adapted to be mounted upon the

motor vehicle and provided with discharge openings through which sand can be distributed in the path of the vehicle wheels, 20 valves, spring means for yieldably holding said valves in position to close said openings, a cable for each valve to open the same, a knob for each of said cables so that the same may be operated to independently open 25 the respective valves, a plate against which said knobs normally rest, and a knob fixed to said plate and whereby the same may be operated to effect simultaneous operation of the two first-mentioned knobs and the 30 valves.

In testimony whereof I affix my signature.

LOUIS H. PETRUS.
